UNITED STATES PATENT OFFICE.

CHESTER H. TEEGARDEN, OF WASHINGTON, DISTRICT OF COLUMBIA.

METHOD OF RECEIVING TELEGRAPH SIGNALS.

Application filed September 9, 1918. Serial No. 253,309.

To all whom it may concern:

Be it known that I, CHESTER H. TEEGARDEN, a citizen of the United States, residing at Washington, in the District of Columbia, have invented certain new and useful Improvements in Methods of Receiving Telegraph Signals, of which the following is a specification.

My invention relates to duplex telegraphy and the object of this invention is to provide a supplementary receiving set which may be attached to a duplex telegraph system to receive all messages transmitted over the system without in any way interfering with the operation of the system.

In the drawings I have illustrated diagrammatically the application of my invention to a duplex telegraph system of the so-called differential type.

Referring to the drawings for a detailed description of my invention, A and B represent two stations of a duplex telegraph system. These two stations are duplicates and a description of one will suffice to describe both. Each station is provided with a differential polarized relay 1 provided with coils 2 and 4. The coil 2 is connected in series between the line 20 and key 3. One terminal of the coil 4 is connected to a terminal of the coil 2 and thus to key 3. The other terminal is connected to the ground 6 through the variable resistance 5. This variable resistance 5 forms what is called the artificial line and is so proportioned that its resistance is equal to that of the line 20. The key 3 is normally held in raised position in engagement with a contact 7 connected to the positive end of battery 9. Upon depression of the key 3 it engages the contact 8 connected to the negative end of battery 9. The mid point of this battery is connected to the ground at 11 by means of a conductor 10.

The relay 1 is provided with an armature 12 movable between a stop 13 and a fixed contact 14, the latter being connected to one terminal of a sounder 16. The other terminal of this sounder is connected to battery 15 and the other terminal of this local battery is connected to the armature 12. The sounder 16 is provided with an armature 17 normally held retracted against the stop 18 by the spring 19.

Assuming the gap 21-22 to be bridged,

the above described parts form the ordinary duplex telegraph line of the differential type and the operation is as follows:—With both keys 3 in the raised position as shown both stations are sending positive potential on to the line 20. These two potentials balance and accordingly no current flows through coil 2. A local current, however, flows at each end as follows:—from battery 9 through contact 7, key 3, coil 4, resistance 5, ground 6, ground 11, and conductor 10 back to battery 9. This current flows through coil 4 in such direction as to move armature 12 against the stop 13, and accordingly the sounder 16 is not energized and no signal is given.

When either of the keys 3 is depressed, for example the key at station A, a negative potential is thrown on the line by that station. With the depression of the key at station A, current will flow from the battery 9 at station B through key 3, coil 2, line 20, coil 2 at station A, key 3, contact 8, left half of battery 9, conductor 10, ground 11 at station B back to battery 9 of that station. This current flows through the coil 2 at station B in such direction as to tend to move the armature 12 against the contact 14. This movement, however, is still opposed by the action of the coil 4. It will be noted, however, that the resistance encountered by the current through coil 2 is substantially the same as that encountered through coil 4 but that the electromotive force driving the current through coil 2 is twice that driving the current through coil 4. The coil 2 will accordingly predominate over the coil 4 and the armature 12 will be moved against contact 14 to energize sounder 16 and indicate the depression of the key at station A and the beginning of the signal. At station A the depression of the key 7 will reverse the current through coil 4 so that coil 4 now tends to move armature 12 against contact 14.

At the same time, however, a current has been set up through coil 2 which flows through the coil in such a direction as to tend to move armature 12 against the stop 13. As previously stated, coil 2 predominates over coil 4 so that armature 12 at station A remains against stop 13 and sounder 16 at station A is not energized. When key 7 at station A is released, the circuits return to normal and armature 12 at station B re-

turns to its position against stop 13, thus causing the deenergization of sounder 16 and permitting the retraction of armature 17 to indicate the termination of the signal. The 5 subsequent depressions and releases of this key 7 will give corresponding attractions and retractions of armature 17.

It is obvious that should the key 7 at station B be depressed, the armature 17 at station A will be similarly actuated. Should the key 7 at station B be depressed during the depression of key 7 at station A, the key at station B will also connect negative potential to the line 20. This will result in no current flowing through to line 20 and coils 2. Accordingly at station A the coil 4 will be unopposed and will cause the movement of the armature 12 against contact 14 to energize sounder 16 and attract armature 17. 15 At station B the depression of key 7 will cause a reversal of the current in coil 4 similar to that which occurred at station A, and cause a similar movement of armature 12 against contact 14, and a similar energization of sounder 16 to attract armature 17. 20 Accordingly both armatures will be attracted to indicate at each station a signal from the other station. When either key is released the condition prevailing will be the same as though that key had not been depressed and this condition will be the same as that previously described and accordingly will cause the retraction of the armature 17 at the station other than that where the key 25 has been released, to indicate at that station the release of the key at the other station and the termination of the signal from the other station.

The above is the operation of the well-known differential duplex telegraph. It will be apparent that four conditions prevail upon the line 20. There may be current flowing in either direction, or there may be no current flowing but maximum potential 45 either positive or negative. My invention utilizes these four conditions to indicate the transmission of messages over the line in either or both directions.

In applying my invention the line is severed at 21-22 and relay 23 is inserted in series with the line. To one terminal of the armature 24 of the relay 23 is connected a conductor 46 which is connected through the reversing switch 35 and conductor 45 to one 55 terminal of the coil 43. The other terminal of this coil is connected through the conductor 42, switch 35, conductor 41, switch 36, conductor 40, to the coil 38 of relay 39. The other terminal of this coil 38 is connected through the conductor 37, switch 36 and conductor 34 to the mid point 33 of battery 31-32. It will be understood that the switches 35, 36, 56 and 57 are normally in 60 their upper position. The positive end of battery 31-32 is connected to contact 29

and the negative end to contact 30, these two contacts being so positioned as to engage the armature 24 in its two extreme positions.

The armature 24 is provided with an insulated insert 25 carrying a contact plug 26, which is normally engaged by the two spring contacts 27 and 28 which serve to hold the armature normally in mid position. The contact 28 is connected to mid point 33 of battery 31-32, while the contact 27 is connected through conductor 55, switch 57, conductor 58, to the coil 59 of relay 39. The other terminal of this coil is connected through conductor 60, switch 57, conductor 61, switch 56, conductor 62, to the coil 63 of relay 44. The other terminal of the coil 63 is connected through conductor 64, switch 56, conductor 65, to armature 51 of a relay 50. The two contacts 52 and 53 of this relay are respectively connected to the negative and positive terminals of battery 31-32 and are so positioned as to be engaged by armature 51 in its two extreme positions. This relay 50 is connected through the variable resistance 48 and variable condenser 49 between the line 20 and the ground.

Relays 44 and 39 are duplicates. Each is provided with two coils as shown and with armature 66 or 67. These armatures are held retracted by springs 68 and 69 and are attracted to the raised position by permanently energized magnets 70 and 71. These magnets are so placed that they are not able to overcome the spring tension and attract the armatures 66 and 67 when the armatures 100 are in their lower position, but the magnets are of sufficient strength to retain the armatures in raised position when they have been so raised by action of the relay coils. It will be seen that the armature of this type 105 relay remains in either extreme position until moved to the other position by a positive force. I make use of this property to prevent chattering of the armature during a shift in relay connections which is not to 110 move the armature to its other position.

The operation of my attachment is as follows:—When no message is being transmitted over the line 20 no current is flowing and the armature 24 is in a neutral position. 115 At the same time positive potential prevails on the line and an instantaneous current has flowed from the battery 9 at both stations into line 20 through variable resistance 48, capacity 49, relay 50, to ground and thence 120 back to both batteries. This energizes relay 50 in such a direction as to cause armature 51 to engage contact 53. This permits a current to flow from battery 31 through contact 53, armature 51, conductor 65, switch 125 56, conductor 64, coil 63, conductor 62, switch 56, conductor 61, switch 57, conductor 60, coil 59, conductor 58, switch 57, conductor 55, contact 27, plug 26, contact 28, conductor 54 back to battery 31. This cur- 130

rent is in such direction in coils 59 and 63 as to retain the armatures 67 and 66 in their normal position. Accordingly no indication of any signal is given by either armature 57 or 66. Should either key 7 be depressed, as for example that at station A, a current will flow through the coil of relay 23 from station B to station A. This will cause the armature 24 to move to the right to engage the contact 30 and simultaneously open the connection between spring contact 27 and spring contact 28. This deenergizes coils 59 and 63. The engagement of armature 24 with contact 30 will complete a circuit as follows:—from point 33 through conductor 34, switch 36, conductor 37, coil 38, conductor 40, switch 36, conductor 41, switch 35, conductor 42, coil 43, conductor 45, switch 35, conductor 46, armature 24, contact 30, back to the negative end of battery 32. This current flows through the coil 38 in such direction as to cause armature 67 to be moved into its raised position and thus indicate the transmission of a message from station A to station B. The current, however, traverses coil 43 in such a direction as not to actuate armature 66. Upon the release of the key at station A current will cease flowing through relay 23 and armature 24 will assume its mid position, at the same time bridging gap 27—28. Return of positive potential to the line will cause the operation of the relay 50 to complete the circuit above described in reference to this relay, and thus to energize the coils 63 and 59. The energization of the coil 63 will be in such direction as to allow armature 66 to remain in position. The energization of coil 59 is in the same direction and accordingly returns armature 67 to its normal or lower position, thus indicating the raising of the key at station A and the termination of the signal. Successive actuation of the key 7 will cause corresponding actuations of the armature 67 thus indicating at the supplementary set all messages sent from station A to station B.

It is obvious from the above description and from the drawings that operation of the key 7 at station B will cause similar actuation of the armature 66 of relay 44, and thus indicate all messages transmitted from station B to station A.

Should both stations be transmitting at the same time, the depression of both keys will throw negative potential on the line. This will cause a current to flow from the ground at the supplementary set through cell 50, capacity 49, resistance 48 to the line and thence in parallel through the two stations to the ground. This energizes coil 50 in such a direction as to throw armature 51 against contact 52. This completes a circuit as follows:—from point 33 through contact 28, plug 26, contact 27, conductor 55, switch

57, conductor 58, coil 59, conductor 60, switch 57, conductor 61, switch 56, conductor 62, coil 63, conductor 64, switch 56, conductor 65, armature 51, and contact 52 back to the negative end of battery 32. This current flows through both the coils 63 and 59 in such direction as to cause both armatures 66 and 67 to assume their raised position and thus indicate the transmission of a signal in each direction. When both keys are raised 75 positive potential will again be on the line, the armature 51 will move over to the contact 53, the current through 63 and 59 will be reversed and armatures 66 and 67 will be moved back into their lower positions to indicate the termination of the signals. Should either signal begin before the other, there will be current flowing through the line at the time the second signal is instituted, but the institution of the second signal will immediately return the armature 24 to mid position, actuate the relay 50 and raise the armature 66 or 67 which is not already raised, leaving the previously raised armature in raised position. Should either key be released before the other, the relay 50 will cease to function, but the relay 23 will come into play to lower armature 66 or 67 corresponding to the raised key and retain in raised position the other armature to thus 95 indicate the cessation of the one signal and the continuation of the other. The circuits and operations under such conditions are believed to be obvious from the drawings and a detailed description thereof is considered 100 unnecessary.

The system which I have described is one in which line 20 normally carries positive potential. While this is one system, some systems are in use wherein the line 105 normally carries negative potential, and others are in use where the one station normally impresses negative potential while the other station normally impresses positive potential. Should either station, for example station A, normally impress negative potential on the line, it is obvious that the armature 67 would be raised to indicate the transmission of a signal to station B at a time when no signal is being transmitted, 110 and would consequently operate reversely. In order to care for such condition, the reversing switches 35—36 and 36—57 have been provided. Under the condition above outlined, the reversing switch 36—57 would be thrown to its lower position to reverse the direction of flow through coils 38 and 59 of relay 39 and thus restore the normal position of armature 67 to that shown in the drawing. If both stations normally impress negative potential on the line, both reversing switches will be thrown into the lower position.

It will be apparent from the above that my receiving set will operate irrespective of 130

the potential normally impressed upon the line by the two usual stations. Further, it will be apparent to those skilled in the art, without further description, that my device is equally applicable to the bridge type of duplex telegraphy or to any type wherein the four conditions of no signal, signals in one direction, signals in the other direction and signals in both directions effect on the line the four conditions of positive potential, current in one direction, current in the other direction and negative potential.

It will be apparent that in case a metallic return is used, the grounded connection of relay 50 would merely be attached to that metallic return. I have used the term ground generically as including such a metallic return. It will further be understood that the terms sounder or relay are used generically and that I do not limit myself in regard to the parts 39 and 44 to a sounder indicating the messages by audible signals, but that I may substitute any appropriate indicating device. It will also be understood that I use the term supplementary receiving set to indicate a set which is attached to an already complete telegraph line to receive messages transmitted over that line independent of those stations essential to the line.

The above modifications and all others which come within the scope of the appending claims I consider to be part of my invention.

35 What I claim is:—

1. A supplementary receiving set for a duplex telegraph line comprising a polarized relay inserted in said line, responsive to current flow in said line and biased to mid-position, two polarized sounders each provided with a first and second coil, an armature for each sounder, connections whereby the first coil of one of said sounders is energized by the operation of the line relay in one direction and the first coil of the other sounder is energized by the operation of the line relay in the other direction, a second polarized relay connection between the line and the ground, connections whereby operation of the second relay in one direction energizes the said second sounder coils in one direction and operation in a reverse direction energizes said second sounder coils in a reverse direction, a switch controlled by the first mentioned relay adapted to open a circuit controlled by the second relay whenever the first mentioned relay is moved out of mid-position, and a plurality of reversing switches each serving to reverse simultaneously both coils of one of the sounders.

2. A supplementary receiving set for a duplex telegraph line comprising a polarized relay inserted in said line, responsive to circuit flow in said line and biased to mid-

position, two polarized sounders each provided with a first and a second coil, an armature for each sounder, connections whereby the first coil of one of said sounders is energized by the operation of the line relay in one direction and the first coil of the other sounder is energized by operation of the line relay in the other direction, a second polarized relay connected between the line and the ground, connections whereby operation of the second relay in one direction energizes the second sounder coils in one direction and operation in a reverse direction energizes the said second sounder coils in a reverse direction, and a switch controlled by the line relay adapted to open the circuit controlled by the line relay adapted to open the circuit controlled by the second relay whenever the line relay is moved out of mid-position.

3. A supplementary receiving set for a duplex telegraph line comprising a relay inserted in said line, responsive to a current flow in said line and biased to mid-position, two sounders each provided with a first and a second coil, the armature of each sounder being normally in retracted position, connections whereby the first coil of one of the sounders is energized by operation of the line relay in one direction and the first coil of the other sounder is energized by operation of the line relay in the other direction, a second relay connected between the line and the ground, connections whereby operation of the second relay in one direction energizes the second sounder coils in one direction and operation in a reverse direction energizes the second sounder coils in a reverse direction, and means responsive to line current for preventing energization of said second sounder coils.

4. A supplementary receiving set for a duplex telegraph line, comprising a relay responsive to current flow in the line, two sounders each provided with a first and a second coil, an armature for each sounder, connections whereby the first coil of one of the sounders is energized by the operation of the line relay in one direction and the first coil of the other sounder is energized by operation of the line relay in the other direction, a second relay responsive to line potential, connections whereby operation of the second relay in one direction energizes the second sounder coils in one direction and operation in a reverse direction energizes said second sounder coils in a reverse direction, and means responsive to line current for preventing energization of said second coils.

5. A supplementary receiving set for a duplex telegraph line comprising a relay inserted in said line, responsive to current flow in the line and biased to mid-position, two sounders each provided with a first and a

- second coil, connections whereby the first coil of one of the sounders is energized by operation of the line relay in one direction and the first coil of the other sounder is energized by operation of the line relay in the other direction, a second relay connected between the line and the ground, connections whereby operation of the second relay in one direction energizes the said second sounder coils in one direction and operation in a reverse direction energizes the second sounder coils in a reverse direction, and means responsive to line current for preventing energization of said second sounder coils.
6. A supplementary receiving set for a duplex telegraph line comprising a relay inserted in said line, responsive to current flow in the line and biased to mid-position, two sounders each provided with a first and a second coil, an armature for each sounder, connections whereby energization of the first coil of each sounder is dependent upon the line relay, a second relay connected between the line and the ground, connections whereby energization of the second coil of each sounder is dependent upon the second relay, and means responsive to line current for preventing energization of said second sounder coils.
7. A supplementary receiving set for a duplex telegraph line comprising a relay inserted in the line and biased to mid-position, two sounders each provided with a first and a second coil, connections whereby energization of the first coil of each sounder is dependent upon the line relay, a second relay connected between the line and the ground, connections whereby energization of the second coil of each sounder is dependent upon the second relay, and means responsive to line current for preventing energization of said second sounder coils.
8. A supplementary receiving set for a duplex telegraph line comprising a relay responsive to current flow in the line, two sounders each provided with a first and a second coil, connections whereby the first coil of one of the sounders is energized by operation of the line relay in one direction and the first coil of the other sounder is energized by operation of the line relay in the other direction, a second relay responsive to line potential, connections whereby operation of the second relay in one direction energizes the second sounder coils in one direction and operation in the reverse direction energizes the second sounder coils in the reverse direction, and means responsive to line current for preventing energization of the said second sounder coils.
9. A supplementary receiving set for a duplex telegraph line, comprising a relay responsive to current flow in said line, two sounders each provided with two in-
- dependent coils, connections whereby the energization of the one coil of each sounder is dependent upon said relay, a relay responsive to line potential, connections whereby the energization of the second coil of each sounder is dependent upon said potential responsive relay, and means responsive to line current for preventing energization of said second coils.
10. A supplementary receiving set for a duplex telegraph line, comprising means responsive to current flow in said line, two sounders each provided with two independent coils, connections whereby the energization of the one coil of each sounder is dependent upon said means, means responsive to line potential, connections whereby the energization of the second coil of each sounder is dependent upon said potential responsive means, and means responsive to line current for preventing energization of said second coils.
11. A supplementary receiving set for a duplex telegraph line, comprising a relay responsive to current flow in said line, two indicating means, each provided with two separate actuating parts, connections whereby the energization of the one part of each means is dependent upon said relay, a relay responsive to line potential, connections whereby the energization of the second part of each means is dependent upon said potential responsive relay, and means responsive to line current for preventing energization of said second parts.
12. A supplementary receiving set for a duplex telegraph line, comprising a relay responsive to current flow in said line, two sounders each provided with two independent coils, means whereby said current responsive means controls the energization of one coil of each sounder, a relay responsive to line potential, means whereby said potential responsive means controls the energization of the second coil of each sounder, and means responsive to line current for preventing energization of said second coil of said sounders.
13. A supplementary receiving set for a duplex telegraph line, comprising means responsive to current flow in said line, two indicating means, each provided with two separate actuating parts, connections whereby the energization of the one actuating part of each indicating means is dependent upon said relay, means responsive to line potential, connections whereby the energization of the second actuating part of each indicating means is dependent upon said potential responsive relay, and means responsive to line current for preventing energization of said second parts.
14. A supplementary receiving set for a duplex telegraph line, comprising means responsive to current flow in said line, two

sounders each provided with two independent coils, means whereby said current responsive means controls the energization of one coil of each sounder, means responsive to line potential, means whereby said potential responsive means controls the energization of the second coil of each sounder, and means responsive to line current for preventing energization of said second coils of said sounders.

15. A supplementary receiving set for a duplex telegraph line, comprising a relay responsive to current flow in said line, two indicating means, each provided with two separate actuating parts, means whereby said current responsive relay controls the energization of one actuating part of each indicating means, a relay responsive to line potential means whereby said potential responsive relay controls the energization of the second actuating part of each indicating means, and means responsive to line current for preventing energization of said second actuating part of said indicating means.

25. 16. A supplementary receiving set for a duplex telegraph line, comprising means responsive to current flow in said line, two indicating means, each provided with two separate actuating parts, means whereby said current responsive means controls the energization of one actuating part of each indicating means, means responsive to line potential, means whereby said potential responsive means controls the energization of the second actuating part of each indicating means, and means responsive to line current for preventing energization of said second actuating part of said indicating means.

35. 17. A supplementary receiving set for a 40 duplex telegraph line comprising a relay responsive to current flow in said line, means for indicating messages being transmitted, means whereby said current responsive relay acts to control said indicating means, a relay responsive to line potential, means whereby said responsive potential relay acts to control said indicating means, and means responsive to line current for preventing control of said indicating means by said potential responsive relay.

45. 18. A supplementary receiving set for a duplex telegraph line comprising means responsive to current flow in said line, means for indicating messages being transmitted, means whereby said current responsive means acts to control said indicating means, means responsive to line potential, means whereby said potential responsive means acts to control said indicating means, and means responsive to line current for preventing control of said indicating means by said potential responsive means.

55. 19. A supplementary receiving set for a duplex telegraph line, comprising indicating means, means responsive to line potential

for normally maintaining the indicating means inoperative, and means responsive to current flow in the line for energizing the indicating means to indicate signal impulses in the line.

70. 20. A supplementary receiving set for a duplex telegraph line, comprising two indicating devices corresponding to the respective line stations, means responsive to line potential for maintaining both indicating devices inoperative when the line is inactive, and means responsive to current flow in the line representing actuation of receiving means at one line station for rendering the corresponding indicating device of the supplementary set operative to indicate the signal impulse in the line.

75. 21. A supplementary receiving set for a duplex telegraph line, comprising two indicating devices corresponding to the respective line stations, means responsive to line potential for maintaining both indicating devices inoperative when the line is inactive, and means responsive to current flow in the line representing actuation of receiving means at one line station for rendering the corresponding indicating device of the supplementary set operative to indicate the signal impulse in the line, and means responsive to unidirectional current flow in the line for maintaining the other indicating device inoperative.

80. 22. A supplementary receiving set for a duplex telegraph line, comprising two indicating devices corresponding to the respective line stations, means responsive to line potential for maintaining both indicating devices inoperative when the line is inactive, means responsive to current flow in the line representing actuation of receiving means at one line station for rendering the corresponding indicating device of the supplementary set operative to indicate the signal impulse in the line, means responsive to unidirectional current flow in the line, 100 for maintaining the other indicating device inoperative, and means responsive to increase in the line potential representing simultaneous operation of both line station receiving means for rendering both indicating devices operative.

85. 23. A telegraph system comprising a line circuit interconnecting two stations, duplex transmitting and receiving apparatus at each of said stations, and a recording device 105 associated with said line circuit at any desired point therein, said recording device including a plurality of relay windings, one of said windings being connected in series with said line circuit, another of said windings being connected as a shunt on said line circuit and a local recording circuit controlled by said windings.

90. 24. A telegraph system comprising a line circuit interconnecting two stations, duplex 110

transmitting and receiving apparatus at each of said stations, and a recording device associated with said line circuit at any desired point therein for recording and signaling impulses originating at either of said stations, said recording device including a local circuit, and relay windings associated in series and in shunt with said line circuit and controlled by the manner of said association with said line circuit, for controlling said local circuit in accordance with the signaling impulses originating at a certain one of said stations.

25. A telegraph system comprising a line circuit interconnecting two stations, duplex transmitting and receiving apparatus at each of said stations, and transmitting apparatus at each station being adapted to apply marking and spacing signaling impulses of positive and negative polarity respectively to said line circuit, and a recording device associated with said line circuit

at any desired point therein for recording the signaling impulses applied to the line circuit at either of said stations, said recording device including a local circuit and a plurality of polarized relay windings, one of said windings being included in series with said line circuit and being controlled by the current flowing over said line circuit 30 as the result of the combined effect of the application of said signaling impulses to said line at each of said stations, the other winding being connected in shunt of said line circuit and being controlled by the current flow over said shunt due to the difference in potential between the sides of said line circuit, said relay windings controlling said local circuit in accordance with the signaling impulses applied to said line circuit 35 at one of said stations.

40 In testimony whereof I have affixed my signature:

CHESTER H. TEEGARDEN.
